PLAY BALL

Mathilde Giesinger, New York, N. Y.

Application May 11, 1942, Serial No. 442,473

1 Claim. (Cl. 273—58)

This invention concerns a resilient play ball of the type used by children and grown-ups for exercise. Such a play ball is usually well balanced, round and preferably spherical. It will bounce off the ground or wall or from the surface of any object substantially in a direction in which a beam of light would be reflected by such surface, if projected thereonto.

It is an object of this invention to provide a ball which, while substantially balanced as to weight, will not bounce off a surface in the accustomed direction, but will deviate from the accustomed path or course of reflection. The use of such ball will necessitate greater skill or agility on part of the players.

On the other hand it is also an object of this invention to provide on a ball of the type just described a surface which allows the ball to rebound in a normal way, if such surface strikes when the ball is bounced.

While providing irregularities as to the surface, I desire to have it centrally balanced as to weight. A preferred ball is divisible into like sectors each having an irregularly formed base.

Other objects of this invention will be learned from the following description. Such description of the invention is rendered by way of the showing of the accompanying drawing and explanation thereof, such description being given by way of illustration and not in limitation of the invention.

In the drawing:

Fig. 1 is a top view and Fig. 2 a corresponding cross-sectioned side view of an embodiment of this invention which is positioned as it would normally rest on a level surface.

Figs. 4 and 3 are corresponding top and side views of another embodiment of this invention, the side view of Fig. 3 being cross-sectioned in part only.

Fig. 5 shows the elevation of still another modification of this invention, the view being partly cross-sectioned.

Similar numerals refer to similar parts throughout the various views.

In a preferred way of realizing the object of this invention the round or spherical surface of

This invention the round or spherical surface of a ball is interrupted in a regular pattern, so that it may strike, when thrown or falling, either at a spherical or at a non-spherical portion of its surface. Such a ball is substantially balanced, i. e., its center of gravity is substantially centrally allocated therein, and there may be symmetry as to integrated like sectors. In a game

the user may apply his or her skill in throwing the ball so that it strikes either at a spherical portion of its surface and rebounds regularly so to speak, or at an eccentric or non-spherical portion of its surface in which case it will rebound in a manner which is difficult to predict.

In the simplest embodiment such a ball, being made of rubber or a similarly elastic material, will be a spherical segment having a zone symmetrical in respect to the great circle as one of its faces, whereas the other faces project, or may be flat, or they may be receded. Such a ball, having for instance concave recesses on opposite sides, is illustrated in Figs. 3 and 4. That embodiment shows a central zone 11 and concave recesses 12 and 13 on opposite sides.

The rebound of such a symmetrical but only partly spherical ball may be controlled by the user with relative ease. It will reflect substantially in the manner in which a fully spherical ball would bounce, if it strikes an object by way of its spherical zone. But when striking at its opposite circular edges, or close thereto, the ball may rebound in a most unexpected manner, and may even strike in short succession at two points of one of those circular edges, before it rebounds as a whole. Geometrically speaking, and disregarding the concavity of the recesses on opposite sides, a play ball of Figs. 3 and 4 may be said to be derived from a sphere by superimposing thereon a solid having comparatively closely spaced, large parallel surfaces. In logical procedure a play ball of this invention may also be produced by intersecting a sphere with an equilateral three-cornered prism. But for purposes of regularity, and in order to offer to the player a ball to which he may systematically apply his skill, I give particular preference to balls segmented in conformity with regular polyhedra superimposed thereupon. Thus a combination of tetrahedron and sphere yields a form of my invention, in which experience and skill may be successfully matched against the uncertainties of a game.

Such a ball, having a spherical portion 14 and the relatively tetrahedrally disposed sides 15, 16, 17 and 18, is embodied in the showing of Figs. 1 and 2.

50 It is understood that hexahedron and octahedron may be similarly incorporated in a ball for purposes of this invention. But I give preference to the tetrahedral-spherical arrangement, because that arrangement is not symmetrical 55 concerning the three planes of a right system

of coordinates, no matter how such a system be placed thereinto, whereas there is such symmetry in respect to a cube as well as an octahedron. For that reason the tetrahedral-spherical embodiment will spin or otherwise perform more like a ball, when thrown, and still the objects of this invention become most pronounced in bouncing.

For like reason I might give preference to a dodecahedral-spherical embodiment, which is regular and symmetrical as to a center point but not as to the three planes of a right system of coordinates, just as the embodiment of Figs. 1 and 2. On the other hand I hesitate concerning the use of the dodecahedron and other polyhedra having a great number of faces, unless they are incorporated in a play ball of this invention executed in a relatively hard, resilient material. When executed in a soft material, a ball with a great many faces will not materially differ as to performance from a round ball. The feature of a substantially unpredictable rebounding of a ball will be more pronounced when the segmental sides of the play ball are large and therefore few in number.

On the other hand I may also provide for purposes of this invention protuberances instead of segmental faces, as interruptions of the spherical continuity of the surface of a play ball, and such protuberances are preferably arranged in a regular pattern, e.g., at the vertices of a polyhedron inscribed to the spherical body. An example of such modification of this invention is illustrated in Fig. 5 where the round protuberances 21 project from the concentrically spherical surface 20 at the vertices of a cube inscribed to the spherical surface. At points 22 or radii normal to the faces of the inscribed cube the spherical surface 20 projects beyond the sides of a cube which may be imaginarily circumscribed around the protuberances 21. Thus the play ball does not offer any particular side of stable support, but may, at best, be said to

have an unstable three-point support by way of one point of the spherical surface 20 and two of the protuberances.

A play ball of this invention may be hollow, as indicated in the showing of Fig. 5, but when embodiments of this invention, which have segmental faces, are made hollow, they are preferably not filled with compressed air or gas, because the gas pressure would push out the faces on the segmental sides, thus frustrating the objects of this invention in that particular instance.

While a device of this invention is hereinabove called a ball, because it is used in the manner of a ball in games, it will be more accurately defined as a play missile in the claim.

Having thus described my invention in detail, yet I do not wish to be limited thereby, except as the state of the art and the appended claim may require, for it is obvious that various modifications and changes may be made in the form of embodiment of my invention, without departing from the spirit and scope thereof.

What I claim is:

25 A play missile comprising a substantially spherical hollow body formed of rubber-like material and having its walls of an even thickness at all points, spaced portions of its walls being projected outwardly to form protuberances, the said protuberances being evenly spaced from each other about the surface of the body and each being of substantially hemispherical shape and at its base merging with portions of the spherical surface of the body between the protuberances, and said protuberances being arranged in pairs disposed in opposite diagonal positions upon the spherical body, the protuberance of each pair being in substantially axial alignment with each other and having their bases substantially in the parallel planes of opposite sides of a parallelogram.

MATHILDE GIESINGER.
